ATTORNEYS

UNITED STATES PATENT OFFICE.

HARRY C. HOLDEN, OF NORWOOD, OHIO, ASSIGNOR TO THE AMERICAN LAUNDRY MACHINERY COMPANY, OF CINCINNATI, OHIO, A CORPORATION OF OHIO.

PUFF IRON.

Application filed August 30, 1922. Serial No. 585,171.

This invention relates to apparatus for the iron, where it disappears or merges, as 55 at 6, Fig. 2, into the rounded heel portion 3.

Said heel end portion is preferably provided on its lower side with an outwardly extending internally threaded socket 7, in which is adapted to be secured the threaded 60 upper end of a standard 9, which forms the support for the puff iron. Said standard is preferably hollow, so that it serves as a conduit for supplying steam or other heating medium to the chamber 10 within the puff 65 iron for heating the same. One suitable location for the puff iron, particularly when steam is the heating medium used, is on the top of the upper pressing member of the machine, the standard or conduit 9 being in 70 communication with the steam chamber in the upper pressing member. In any event, the puff iron will be so located that it is convenient for use by the operator of the pressing machine.

The puff iron is preferably so constructed 75 that it may be secured to the standard 9 in an angular position, with its longitudinal or major axis inclined to the vertical, as clearly indicated in Fig. 1. The puff iron is also 80 preferably secured to its support at the heel end, with its pointed toe end extending upwardly and forwardly, so that it is easily accessible to the operator.

The point 5 of the toe end easily enters 85 the folds, ruffles, etc. of the garment, so that all of those portions so difficult to reach are properly ironed. The longitudinally extending sharp ridge 6, in addition to entering 90 the folds, etc. of the garment and assisting in the ironing of those portions, also forms a resistance, as distinguished from the smooth rounded surfaces of prior constructions, for the work as it is drawn back and forth thereover by the operator, so that 95 the most deep seated wrinkles may be smoothed or ironed out. The inclination of the puff iron greatly facilitates and increases 100 the speed of the ironing operation, not only by rendering the pointed nose end of the puff iron more accessible to the operator, but by providing an inclined surface or edge over which the work may be pulled rather than pushed, with the resultant increased pressure and effect.

Other objects of the invention will be apparent to those skilled in the art to which it relates.

In the pressing of garments and the like 5 by pressing machines comprising two relatively movable pressing members between which the garment is pressed, it is impossible to reach and properly iron certain portions of the garment, such as ruffles, pleats, 10 tucks, etc., so that it is customary to employ with such a machine a puff iron for the ironing of those parts. The ordinary puff iron comprises a hollow, smooth surfaced member of spherical, oval or other form, which 15 is suitably heated and located at any convenient place on or near the pressing machine. In use, said puff iron is held stationary and those portions of the garment to be ironed by the puff iron are moved back 20 and forth over the surface thereof by the operator of the pressing machine.

The object of the present invention is to provide an improved puff iron which is formed with a pointed nose portion and a 25 longitudinally extending sharp ridge portion, enabling all parts of the ruffles, folds, etc., to be reached and properly ironed, the ridge portion also forming a resistance for the work as it is moved back and forth 30 thereover.

A further object of the invention is the angular arrangement of the present puff iron on its support, which greatly facilitates and increases the speed of the ironing operation.

Further objects of the invention are in part obvious and in part will appear more in detail hereinafter.

In the drawing, which illustrates one suitable embodiment of the invention, Fig. 1 is a side elevation, partly broken out and in section to show the manner of securing the puff iron to its support; Fig. 2 is an elevation of the heel end of the iron; and Figs. 45 3 to 7 are detail sectional views on the lines 3-3 to 7-7, Fig. 1, respectively.

Referring to the drawing, the puff iron comprises a hollow, substantially smooth surfaced egg-shaped member 1, having a pointed toe end portion 2 and a rounded heel end portion 3. Said puff iron is formed with a longitudinal, sharp ridge or edge 4, extending from the point 5 of the toe end portion back over a portion of the top of

What I claim is:—

A puff iron, comprising a substantially ovoid body having a rounded heel end portion and a substantially pointed toe end portion, said body near the heel end portion being provided with means for attaching it to a support with its rounded heel end exposed, said body being so formed that its upper surface when on said support has a rela-

tively sharp ridge extending from the toe 10 end toward the heel end, said pointed toe and ridge being thereby presented upwardly for use in opening or ironing pleats, ruffles, folds or the like.

In testimony whereof I hereby affix my 15 signature.

HARRY C. HOLDEN.
